UNITED STATES PATENT OFFICE.

STANLEY B. NOVOTNY AND ROY JACKMAN, OF CEDAR RAPIDS, IOWA.

VEHICLE-LAMP.

1,085,469.

Specification of Letters Patent. Patented Jan. 27, 1914.

Application filed January 7, 1913. Serial No. 740,656.

To all whom it may concern:

Be it known that we, STANLEY B. NOVOTNY and ROY JACKMAN, citizens of the United States, residing at Cedar Rapids, in the county of Linn and State of Iowa, have invented new and useful Improvements in Vehicle-Lamps, of which the following is a specification.

It is customary in the operation of vehicles, particularly of the type mechanically driven to require identification numbers to be placed in a conspicuous place for observation, and in order that such numbers may be discernible at night it is necessary that they be located near a lamp, the two being so placed as to admit of the lamp shedding its rays of light upon the number plate. Different localities or jurisdictions have different numbers, hence when a vehicle is passing from one municipality to another it becomes necessary either to change or to shift the position of the number plate so that the latter may be easily read after dark.

The present invention provides a lamp which admits of the number or identification plate being easily and quickly changed and of locating the same directly in the path of the rays of light so as to insure its being easily read at night, said number plate being preferably of stencil form so that any color of light may be exposed, thereby admitting of the lamp shedding a red light when used as a rear lamp which is usually required to display a red light in the rear to prevent rear-end collision.

The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a perspective view of a vehicle lamp embodying the invention. Fig. 2 is a side view. Fig. 3 is a horizontal section. Fig. 4 is a detail perspective view of the reinforcing bracket.

Corresponding and like parts are referred to in the following description, and indicated in all the views of the drawings, by the same reference characters.

The lamp comprises a lantern embodying bodies 1 and 2. The body 1 in plan view is preferably of approximately triangular form and the body 2 is of cylindrical form and located at the apex or juncture of the

converged sides of the body and projects above and below the same. The body 1 has its front open and the walls have their edge portions adjacent the open front bent outwardly to form flanges for supporting the number and transparent plates. A lamp 3 is removably fitted within the lower end of the body 2 and is adapted to have the wick raised or lowered through an opening 65 formed in a side of such body, which opening is normally closed by means of a slide 4. When the slide 4 is moved to expose the opening the wick raising means is accessible for operation. The parts 1 and 2 may be of any construction common in the art.

A bracket is provided for attaching the lamp to a vehicle and also serves to reinforce the lamp and as means for retaining the number and transparent plates in position. The bracket comprises similar members, each member consisting of a horizontal portion 5, a vertical portion 6, a rearwardly bent end 7, a curved portion 8 and a rear extension 9. When the two numbers 80 are in position the curved portions 8 embrace opposite sides of the lower portion of the lamp body and their rear extensions 9 are connected by means of a bolt or other fastening. One of such rear extensions being bent to form an attaching part 10, which may be fastened to the vehicle in any manner. The horizontal portions 5 extend beneath the side portions of the body 1 and are bolted or otherwise secured thereto. The vertical portions 6 extend in front of the sides of the body 1 and are spaced therefrom and are connected thereto by means of bolts or fastenings 11. The bent ends 7 overlap end portions of the top of the body 1 and 90 are secured thereto by suitable fastening means. Projections 12 are formed upon the inner or rear faces of the vertical portions 6 at the ends thereof to engage the inner flanges of the sides of the body 1 to space 100 the parts 6 and to form shoulders for the upper and lower edges of the transparent and number plates to engage so as to prevent vertical displacement thereof. Each member of the reinforcement is preferably 105 constructed of a bar bent in the shape substantially as set forth. The bolts or fastenings 11 extend across the spaces formed between the parts 6 and the adjacent portions of the body 1 to prevent displacement 110 or endwise movement of the plates.

The number plate 13 is slipped into posi-

2
tion by an endwise movement after one of the fastenings 11 has been removed and is retained in place by means of the fastenings 11 and the projections 12 in the manner 5 stated. The number plate is of the form of a stencil, the numbers being cut therefrom so that the lamp may shed rays of light through the numbers, thereby admitting of the latter being easily read after dark. A 10 transparent plate 14 is interposed between the number plate 13 and the lantern body and may be suitably colored to display any color of light that may be required. When the lamp is particularly designed for use as 15 a tail-light on vehicles the plate 14 is colored to display a red light which is generally required to indicate danger and prevent rear-end collision. The plates 13 and 14 are practically of like size and when in position 20 cover the open front of the lantern body and are retained in place by means of the vertical portions 6 of the reinforcing members. Upon removal of one or the other of the fastenings 11 the number plate 13 may be 25 easily and quickly removed and another plate slipped into position so as to expose a different number when passing from one jurisdiction to another. The transparent or translucent plate 14 is usually of glass and 30 may be plain or colored in any manner according to the specific requirements and uses of the lamp.

From the foregoing description, taken in connection with the accompanying drawings, the advantages of the construction and 35 of the method of operation will be readily apparent to those skilled in the art to which the invention appertains, and while we have described the principle of operation of the 40 invention, together with the device which we now consider to be the best embodiment thereof, we desire to have it understood that the device shown is merely illustrative, and that such changes may be made when desired 45 as are within the scope of the claims appended hereto.

Having thus described the invention what is claimed as new, is:—

30 1. A vehicle lamp comprising a lantern body having an open front, members at the

ends of the open front secured at their ends to the lantern body and having the portions intermediate of their ends adjacent to and spaced from the lantern body, a number plate closing the front of the lantern 55 and removably fitted between it and the spaced portions of the before mentioned members and fastening means connecting the said members to the lantern body and engaging the ends of the number plate to 60 retain it in place.

2. A vehicle lamp comprising a lantern body having an open front, reinforcing members having their end portions overlapping the top and bottom of the lantern body 65 and secured thereto and having the intermediate portions adjacent the ends of the lantern body spaced therefrom, a number plate closing the front of the lantern body and removably fitted between it and the 70 reinforcing members and fastening means for securing the spaced portions of the reinforcing members to the side members of the lantern body and engaging and retaining the number plate in position. 75

3. A vehicle lamp comprising a lantern embodying front and rear bodies, the front body being approximately of triangular form in plan view and having its front open and the rear body being cylindrical and in 80 communication with the front body and extending above and below the same, a number plate closing the front of the lantern, and reinforcing members of similar form each having a part extending over the top of the 85 front body, thence down in front thereof to confine the number plate, thence beneath the bottom of the front body and around a side of the rear body and terminating in a rear extension, the rear extensions of both reinforcing members being connected and one of said members having means for securing the lamp to a suitable support. 90

In testimony whereof we affix our signatures in presence of two witnesses:

STANLEY B. NOVOTNY.
ROY JACKMAN.
